(57) **CLAIM**

The ornamental design for a space configuration design tool,
as shown and described.

DESCRIPTION

FIG. 1 is a perspective view of the present invention;
FIG. 2 is a right side view thereof, the left side view being
identical;

FIG. 3 is a back view thereof;

FIG. 4 is a front view thereof;

FIG. 5 is a top view thereof;

FIG. 6 is a bottom view thereof; and,

FIG. 7 is a perspective view thereof, further showing a
support wand associated therewith.

The broken line showing is for illustrative purposes only and
forms no part of the claimed design.
